UNITED STATES PATENT OFFICE.

CHARLES PHILLIPS, SR., OF BOLIVAR, NEW YORK.

WORKING VALVE FOR OIL-WELL PUMPS.

Application filed August 9, 1921. Serial No. 490,827.

To all whom it may concern:

Be it known that I, CHARLES PHILLIPS, Sr., a citizen of the United States of America, and resident of Bolivar, county of Allegany, 5 and State of New York, have invented certain new and useful Improvements in Working Valves for Oil-Well Pumps, of which the following is a specification.

This invention relates broadly to pumps 10 for oil and artesian wells, and more particularly to a check valve and valve cage for the plungers or working valves of such pumps.

The primary object of the invention is to 15 provide a working valve of a type commonly employed in oil wells, having a construction designed to insure the reseating of the usual ball-check valve after each suction stroke, thus preventing the chattering which is com- 20 monly produced by gas rising under pressure through the working valve and which frequently interferes seriously with the proper working of oil well pumps.

With this and other objects in view, the 25 invention resides in the features of construction and arrangement of parts which will hereinafter be fully described, reference being had to the accompanying drawings, in which—

30 Figure 1 is a side elevation of the upper portion of a working valve of an ordinary type, showing my invention applied thereto;

Figure 2 is a longitudinal section on line 35 2—2, Fig. 1; and—

Figure 3 is a transverse section on line 3—3, Fig. 1.

Referring to said drawings, 1 indicates the upper end portion of the hollow body 40 of a plunger or working valve of a type more or less commonly employed in oil-well pumps, the same carrying the usual leather cups 2. Threaded within the upper end of said working-valve body is a short thimble 3 having its upper end shaped to form a seat 3^a for a ball-check valve 4.

Threaded exteriorly upon the upper end of the working-valve body is the lower end of a cylindrical cage 5 provided with one or 50 more side openings 6, preferably two, three, or four, for the outward passage of fluid which passes the valve 4 in the down stroke of the tool. Said cage has an integral reduced stem 7 adapted for coupling to a sucker rod, and provided within said stem 55 is a socket 8 designed for the reception of a

light spiral spring 9 whereby said valve 4 is normally maintained seated under yielding tension. An inverted cup 10, which loosely seats upon said valve 4, has an upright stem 11 embraced by the lower end portion of said spring 9.

In practice, the valve 4 is lifted in the usual manner on each suction stroke of the tool, permitting the fluid to pass thereby to the interior of the cage 5, whence it passes outward through the openings or ports 6. Free passage of such fluid in an upward direction is permitted by the provision in the cylindrical wall of said cage of external vertical channels 12 which lead upward from each of said ports to the lower end of the reduced stem 7, as shown. Promptly following such suction stroke the spring 9 actuates the valve 4 to return to its seated position.

The spring is made of such tension that, while it permits unseating of the valve in the suction stroke, it will resist the pressure of gas in the well which tends to unseat the valve following such stroke. Thus, chattering of said valve due to the presence of gas is effectually prevented, and the gas is consequently required to pass upward outside the well casing.

It is to be understood that the valve and cage structure described is not limited to any particular style or type of pump, but is readily applicable to practically any of the types employing ball-checks. Further, the stem may have any desired form of end joint for coupling to the pump or sucker rod or line.

What is claimed is—

1. In a pump for oil wells, a working valve comprising a plunger body having a valve seat at its upper end, a cage threaded exteriorly upon said upper end, said cage having longitudinal channels in its outer surface and having ports opening into said channels, a ball-check valve enclosed by said cage and movable into and out of seating relation to said seat, an inverted cup resting on said valve and having an upright stem, and a spiral spring having one end seated upon said cup in embracing relation to said stem, said spring normally holding said valve to its seat.

2. A traveling valve construction for well pumping apparatus comprising the combination with a tubular pump-casing presenting a valve seat, a valve cage above the seat

and a spring pocket above the valve cage, its lower end pressed against the latter at 10
of a ball within the said cage, a cap-piece
engaging the said ball and having an up-
wardly projecting stem adapted on the up-
ward movement of the ball to enter the said
spring pocket, and a spring compressed be-
tween the upper face of the cap-piece and
the end wall of the said spring pocket and
encircling the stem of said cap-piece with

the base of the stem.

In testimony whereof, I affix my signature
in presence of two subscribing witnesses.

CHARLES PHILLIPS, Sr.
